PRODUCTION OF BUTADIENE

William J. Mattox, Chicago, Ill., assignor to Universal Oil Products Company, Chicago, Ill., a corporation of Delaware

Application February 11, 1942, Serial No. 430,496

6 Claims. (Cl. 260—680)

This is a continuation in part of my co-pending application, Serial No. 348,976, filed July 31, 1940.

This invention relates to a process for the catalytic cracking and dehydrogenation of hydrocarbon fractions to produce diolefins, particularly butadiene.

One of the most important processes for the production of synthetic rubber is the butadiene polymerization process or the butadiene-styrene copolymerization process. Processes, therefore, which result in the formation of reasonably large quantities of butadiene are particularly important since the production of synthetic rubber is at present limited by the production of butadiene.

I have found that by cracking hydrocarbon fractions comprising essentially C₆ to C₁₂ hydrocarbons, mainly olefins, that relatively large amounts of normal C₄ olefins can be produced and that these C₄ olefins may be readily converted to butadiene by dehydrogenation, preferably catalytic. I have found, furthermore, that one of the most suitable charging materials for the catalytic cracking step to produce normal butenes is polymer gasoline formed by polymerization of C₂, C₃, and C₄ olefins. I have also found that isobutene, which is produced to some extent by the cracking and dehydrogenation steps, and which cannot readily be converted to butadiene, may be isomerized to normal butenes by contacting it with a cracking catalyst at moderately high temperatures. Therefore, I propose a combination catalytic cracking and dehydrogenation process in which high yields of butadiene may be obtained from an olefinic charging stock by converting the higher boiling olefins to normal C₄ olefins followed by dehydrogenation of the C₄ olefins to butadiene, with return of the unconverted C₄ hydrocarbons, including isobutene, to the cracking step.

In one specific embodiment, the present invention comprises a process for the production of butadiene which comprises catalytically cracking a hydrocarbon oil comprising essentially C₆ to C₁₂ hydrocarbons, mainly olefins, to produce lower boiling olefins, separating from the resultant products a fraction comprising butenes and a higher boiling fraction, returning said higher boiling fraction for further catalytic cracking, dehydrogenating said fraction comprising butenes in the presence of a dehydrogenating catalyst to produce butadiene, separating butadiene from the resultant conversion products and returning the remaining C₄ hydrocarbons including isobutene to the aforementioned catalytic cracking treatment to isomerize said isobutene to normal butenes.

The accompanying drawing illustrates diagrammatically in side elevation one specific form of apparatus that may be employed in accomplishing the objects of this invention.

Referring now to the drawing, a hydrocarbon fraction consisting essentially of C₆ to C₁₂ hydrocarbons, mainly olefins, is supplied through line 1, valve 2, pump 3, line 4 and valve 5 to heating coil 6 disposed in furnace 7 wherein the hydrocarbon oil is heated to a temperature in the range of from about 750 to 1150° F., preferably about 850 to 1100° F. and at a pressure that may vary from slightly superatmospheric to 100 pounds or more per square inch. The resulting heated hydrocarbons are supplied through line 8 and valve 9 to catalytic reactor 10 wherein they are contacted with a cracking catalyst for a sufficient length of time to result in the formation of lower boiling olefins, particularly C₄ olefins.

Catalytic reactor 10 may be either of the type in which heat is supplied to the catalytic mass by means of a heat convective medium or it may be of the type in which substantially all of the heat of reaction is supplied to the reaction by means of the high heat content of the incoming oil. Catalytic reactor 10 contains, preferably, a bed of catalyst consisting essentially of an association of silica and alumina, the catalyst being either a naturally occurring compound or synthetically prepared. The catalyst may be granular and arranged in beds so that the flow of the hydrocarbon vapors is conducted down through the beds or the catalyst may be in the powdered form, maintained in a turbulent state by an upwardly rising stream of hydrocarbon vapors.

Regeneration of the catalyst is usually necessary and such regeneration may be accomplished in situ by the passage of oxygen containing gases through the catalytic mass. If desired, however, the catalyst may be removed either periodically or continuously and regenerated in a separate regeneration zone.

Returning now to the drawing, conversion products from reactor 10 are supplied through line 11 and valve 12 into fractionator 13 wherein a fraction consisting of C₃ and lighter hydrocarbons, a fraction comprising C₄ hydrocarbons, and a higher boiling fraction are separated. The light fraction is withdrawn through line 14 and valve 15 and the heavy fraction is returned to the catalytic cracking step through line 16 and valve 17 and line 35. The C₄ fraction which consists not only of normal butenes but also of isobutene and butanes is withdrawn from fractionator 13 through line 18, valve 19, pump 20, line 21, and valve 22 and is supplied to heating coil 23 contained in furnace 24 wherein the C₄ fraction is heated to dehydrogenating conditions. The resulting heated hydrocarbons are supplied through line 25 and valve 26 to dehydrogenation reactor 27 wherein they are contacted with a dehydrogenation catalyst to effect dehydrogenation of a portion thereof to butadiene.

Reactor 27 may be of the type in which the hydrocarbon vapors are passed through a bed of

granular dehydrogenation catalyst or it may be of the type in which the hydrocarbon vapors are passed upward through a turbulent bed of powdered catalyst. In either case, it is usually desirable that the reactor be equipped with heat exchange surfaces so that the endothermic heat of dehydrogenation may be supplied to the reactants therein.

The catalyst which is preferred for the dehydrogenation comprises chromium oxide on a support such as activated alumina. However, it should be noted that many other catalysts such as vanadium oxide, molybdenum oxide and the like have been found quite suitable. Furthermore, other supports such as clay and magnesia have been found suitable, although not usually as satisfactorily as activated alumina.

In the reactor it is usually desirable that the temperatures be maintained within the range of from about 1000° F. to about 1300° F. although in some cases it is possible to effect dehydrogenation above or below the preferred temperature range. Furthermore, it is desirable and, in fact, necessary in order to prevent undue decomposition, to employ low pressures in the dehydrogenation reactor. It is usually desirable that the partial pressure of the hydrocarbons undergoing reaction be maintained below about 300 mm. mercury absolute and it is preferred, in fact, that the hydrocarbon partial pressure be held below about 200 mm. mercury absolute. Under these conditions, high yields of butadiene may be obtained without excessive carbon formation and without undesirable side reactions occurring to any great extent.

The reaction products from dehydrogenation reactor 27 are supplied through line 28 and valve 29 to butadiene separation zone 30 in which a separation is effected between butadiene, other C₄ hydrocarbons, and C₃ and lighter products. It is usually necessary in order to obtain a reasonably pure butadiene to employ not only the customary absorption and stripping methods to separate a C₄ fraction from lighter and heavier products but also to employ special separation methods to make separations within the C₄ fraction, that is, to separate butadiene from the remaining C₄ hydrocarbons. For this reason, the butadiene separation zone may comprise a solvent extraction step, an azeotropic distillation step, or some other process for removing butadiene selectively. C₃ and lighter reaction products separated in zone 30 are removed through line 31 and valve 32. Butadiene is removed as a product of the process through line 33 and valve 34. The remaining C₄ hydrocarbons, a large proportion of which is isobutene, are withdrawn from the separation zone through line 35 and valve 36 and are returned to the catalytic cracking step. The isobutene present therein is then isomerized in the cracking zone to normal butenes, which may be readily dehydrogenated to butadiene.

The following example is given to illustrate the operating conditions which may be employed in accomplishing the results of this invention.

Example

A polymer gasoline consisting predominantly of C₆ through C₁₀ olefins is heated to a temperature of about 930° F. and contacted with a synthetic silica-alumina catalyst prepared by compositing silica hydrogel with alumina hydrogel followed by a calcination treatment. The resulting products of reaction of which C₄ olefins are a large proportion are fractionated to separate a C₄ frac-

tion from a lighter fraction comprising C₃ and lighter materials and a heavier fraction comprising C₅ and heavier materials. The lighter fraction is withdrawn and the heavier fraction is returned to the catalytic cracking treatment. The C₄ fraction is heated to a temperature of about 1175° F. and contacted with a chromia-alumina catalyst at a pressure of about 100 mm. mercury absolute for a sufficient length of time to result in a conversion of a substantial portion of the C₄ olefins and paraffins to butadiene. The C₄ fraction is separated from the other decomposition products by an absorption, stripping operation. The butadiene is separated from the remaining C₄ hydrocarbons by a step comprising azeotropic distillation, the resultant butadiene is recovered, and the remaining C₄ fraction, comprising a large proportion of isobutene, is returned to the catalytic cracking step to isomerize the isobutene to normal butenes.

I claim:

1. A process for the production of butadiene which comprises subjecting an olefinic distillate at cracking conditions to the action of a cracking catalyst to form C₄ olefins, subjecting resultant C₄ olefins at dehydrogenating conditions to the action of a dehydrogenating catalyst to form butadiene incidental to which a minor quantity of isobutene is formed, separating from the resultant conversion products a butadiene fraction and a fraction comprising unconverted C₄ olefins and the isobutene, supplying the latter fraction to the cracking step, whereby to isomerize the isobutene into normal butene, and supplying the normal butene thus formed to the dehydrogenating step together with the C₄ olefins produced by the catalytic cracking.
2. The process of claim 1 further characterized in that the olefinic distillate comprises polymer gasoline.
3. A process for the production of butadiene which comprises subjecting an olefinic distillate at cracking conditions to the action of a cracking catalyst to form C₄ olefins, subjecting resultant C₄ olefins at dehydrogenating conditions to the action of a dehydrogenating catalyst to form butadiene incidental to which a minor quantity of isobutene is formed, supplying isobutene thus formed to the catalytic cracking step, whereby to effect conversion thereof into normal butene, and supplying the normal butene thus formed to the dehydrogenating step together with the C₄ olefins produced by the catalytic cracking.
4. The process of claim 3 further characterized in that the cracking catalyst comprises a synthetic composite comprising silica and alumina.
5. The process of claim 3 further characterized in that the olefinic distillate comprises polymer gasoline.
6. A process for the production of butadiene which comprises subjecting polymer gasoline at cracking conditions to the action of a cracking catalyst to effect conversion thereof into C₄ olefins as the principal reaction, subjecting resultant C₄ olefins at dehydrogenating conditions to the action of a dehydrogenating catalyst to form butadiene incidental to which a minor quantity of isobutene is formed, supplying isobutene thus formed to the catalytic cracking step, whereby to effect conversion thereof into normal butene, and supplying the normal butene thus formed to the dehydrogenating step together with the C₄ olefins produced by the catalytic cracking.
